(57) CLAIM

The ornamental design for a footwear outsole, as shown and described.

DESCRIPTION

FIG. 1 is a front top perspective view of a footwear outsole showing the outsole design.

FIG. 2 is a front bottom perspective view of the footwear outsole of FIG. 1.

FIG. 3 is a bottom plan view of the footwear outsole of FIG. 1.

FIG. 4 is a top plan view of the footwear outsole of FIG. 1.

FIG. 5 is a right side view of the footwear outsole of FIG. 1.

FIG. 6 is a left side view of the footwear outsole of FIG. 1.

FIG. 7 is a front elevation view of the footwear outsole of FIG. 1.

FIG. 8 is a rear elevation view of the footwear outsole of FIG. 1.

FIG. 9 is an enlarged detail view of the portion of the footwear outsole labeled 9 in FIG. 2.

FIG. 10 is a partially schematic cross-sectional detail taken along the line 10-10 in FIG. 3 to illustrate dimensions of a portion of the footwear outsole of FIG. 3; and,

FIG. 11 is a partially schematic cross-sectional detail taken along the line 11-11 in FIG. 3 to illustrate dimensions of a portion of the footwear outsole of FIG. 3.

The dashed lines shown in the drawings illustrate portions of the footwear and footwear outsole that are not presently claimed and thus form no part of the presently claimed design. The shading lines shown in the drawings represent the approximate three-dimensional contour of the claimed design and are not intended to indicate surface decoration.

1 Claim, 10 Drawing Sheets
